UNITED STATES PATENT OFFICE.

RICHARD VARLEY, OF ENGLEWOOD, NEW JERSEY, ASSIGNOR TO VARLEY DUPLEX MAGNET COMPANY, OF JERSEY CITY, NEW JERSEY. A CORPORATION OF NEW JERSEY.

IGNITION SYSTEM AND APPARATUS.

1,071,373.

Specification of Letters Patent. Patented Aug. 26, 1913.

Application filed October 10, 1912. Serial No. 724,928.

To all whom it may concern:

Be it known that I, RICHARD VARLEY, a citizen of the United States of America, residing at Englewood, in the county of Bergen and State of New Jersey, have invented certain new and useful Improvements in Ignition Systems and Apparatus, of which the following is a full, clear, and exact description, reference being had to the accompanying drawings, which form part of this specification.

This invention relates to ignition systems for explosion engines and has particular reference to that part of the system known as the timer or controller whereby the ignition circuit is opened or closed in proper synchronism with the engine cycle.

The primary object of the invention is the provision of a timer or similar apparatus in which the contact members or associated parts are relieved from constant contractual shifting or operative vibration when not employed in ignition capacity, as when the timer is in an auxiliary circuit or equipment used only in starting or in slow running of the engine which at other times utilizes a separate or magneto or dynamo ignition circuit.

In the employment of a dual ignition system or alternative dynamo or magneto generator and battery equipment, non-use (electrically) of the timer in the circuit of one source of current during the utilization of the other current source, does not render the timer, as heretofore constructed, mechanically inoperative during running of the engine. The result is that, although the timer is utilized infrequently and for periods of short duration, for the remainder of the time it continues to be mechanically driven (usually at high injurious speed) with attending ready and excessive needless wear or mutilation and consequent short life of the timer contacts and bearing points. I also aim to so construct my timer or controller that it shall not materially vary structurally from the regular standard types of timer; that it shall be compact and symmetrical; and shall have the minimum number of parts.

In describing my invention I will refer to the accompanying drawing showing, partly diagrammatic, my invention as applied to several types of ignition timers or controllers. It will be apparent, without necessity

of specific illustration, to those skilled in the art, that my invention is equally applicable to other forms of timers, and I do not therefore desire to limit myself thereto.

Figure 1 is a top plan view of a timer or ignition controller embodying my invention, the contacts being closed; Fig. 2 is a similar view, the contacts being shown as in an inoperative condition mechanically and electrically; Fig. 3 is a longitudinal sectional view on the line 3-3 of Fig. 1; Fig. 4 is a diagrammatic view, showing electrical connections of the timer of the preceding view; Fig. 5 is a similar view showing my invention as applied to an interrupter mechanism to be hereinafter more fully described; Fig. 6 is a top plan view of a timer of the roller type, embodying my invention, and showing the contacts separated; Fig. 7 is a section on the line 7-7 of Fig. 6; Fig. 8 is a top plan view showing the timer in an operative condition; Fig. 9 is an enlarged fragmentary section on the line 9-9 of Fig. 8; Fig. 10 is a diagrammatic view showing the ignition circuit of the roller timer; Fig. 10^a is a fragmentary diagrammatic view showing electrical connection of the roller contact arm and magnet; Fig. 11 is a diagrammatic view showing my invention as applied to an ordinary spring-arm timer; Fig. 12 is a similar view showing my invention as applied to a multiple arm timer; the arm shifting members being removed; Fig. 13 is a top fragmentary plan view showing the contact arms in operative position; Fig. 14 is a similar view showing the arms shifted to inoperative or noncontact position; Fig. 15 is a section on the line 15-15 of Fig. 13; and Fig. 16 is an enlarged fragmentary perspective view showing relative arrangement of shifting member and contact arms.

Referring to Figs. 1 to 4 inclusive, I have shown a type of controlling device wherein a movable contact is rocked or oscillated by a cam through the intermediary of a spring pressed reciprocable lever. The movable contact 2 is preferably carried by a spring arm or yieldable lever 3, pivoted to the base piece 4 of the timer casing 5 and normally held in non-closing position against a stop 6 by a coiled spring 7. From a fulcrum piece 8 leads a lever 9 interposed between the lever 3 and a revoluble cam 10. The cam 10 is formed on a head piece 11 which

is mounted on the usual timer shaft 12 geared to be driven commensurately by the engine, in a well known manner, and is provided with symmetrically disposed shoulders or projections 13 which upon rotation of the cam engage a head or shoulder 14 on the intermediate lever 9, carrying the lever upward to a position for engagement with a bearing point 15 of the contact lever 3 for movement of the contact 2 into engagement with a fixed contact 16. A spring 17 returns the lever 9 upon the latter's release from a moving projection 13 preparatory to its engagement by the next advancing projection on the cam, and as said lever 9 is released it rides over the curved face of the projection, being forced outwardly thereby and into engagement with the bearing point 15 so as to move the contact 2 against the contact 16. This action is quick and decisive, the contact being instantaneously made and broken as the lever 9 passes from and over the cam projection. The base 4 is rotatably shiftable about the head 11 for adjustment of the lever 9 relatively to the cam projections, to advance or retard the spark, as is well understood by those skilled in the art. For this purpose the timer casing has the usual adjusting arm 18. Pivoted at 19 to the base 4 or frame of the timer, is a lever 20 having a terminal portion 21 adjacent the lever 9 and an arm 22 which forms an armature for the magnet 23. The contact 16 is preferably insulated and connected in circuit with the battery 24 (or other source), while the contact lever 3 and, therefore the contact 2, is preferably grounded. The magnet 23 is connected at 25 with the battery circuit and also grounded (through the timer frame) at 26 so that it is in shunt therewith. A customary ignition circuit is shown with an intercalated primary coil 27, a secondary coil 28 leading to distributor 29, and a condenser 30 having a live connection with the primary circuit and grounded, while the numeral 31 indicates a switch which may be located at any convenient point on the vehicle and by which the circuit is connected and disconnected with the battery.

Normally the lever 9 is held out of operative position or free from engagement with the traveling projections on the cam 10 by a spring 32 which holds the lever 20 in such a position as to bring the nose or terminal portion 21 thereof into the path of the lever 9, as shown in Fig. 2. A suitable stop 33 prevents the lever 20 from crowding the lever 9 against the adjoining contact lever. Upon closing of the switch 31 and energizing of the magnet 23 the arm 22 moves toward the magnet, swinging the lever 20 and retracting the nose 21 and allowing the lever 9 to move, under the action of the spring 17 into engagement and coöperation with

the cam for operative oscillatory shifting of the contact lever 3. Immediately upon de-energizing of the magnet the spring pressed lever 20 will again move to the position shown in Fig. 2, forcing the lever 9 from the path of the moving cam projections. When the lever 9 occupies the inoperative position shown in Fig. 2, a stop or lug 34 serves to overcome such downward shifting of the said lever by the spring 17, as would prevent reengagement of lever and cam when the lever 20 is attracted or in the position shown in Fig. 1. Very little battery current is used as the tension of the spring 32 need be very slight to shift the lever 9 from the cam and the magnetic force required to overcome the spring pressure is therefore not great and furthermore the magnet is only energized during utilization of the timer.

In Fig. 5 I show that type of controller wherein the primary circuit 35 is momentarily interrupted by separation of the contacts 2 and 16; the condenser 30' discharging through the primary circuit 35, the primary coil 27 and producing a high tension current in the secondary winding or coil 28 in a well known manner. The cam 36 has projections 13' which in number correspond to the cylinders of the engine, as in the case of timer shown in Figs. 1 to 4. The contact lever 3' is preferably grounded while the contact 16 is insulated and connected directly in the battery circuit. The numeral 37 indicates a pivoted lever or armature which coöperates with the magnet 23, to hold, through the medium of a coil spring 38, the insulated bearing block 39 of the lever 3' against the cam 36, when said magnet is energized. Upon disconnection of the battery and deenergizing of the magnet 23 and resultant reduction of tension of the spring 38, a spring 40 leading to lever 3' will draw the latter lever away from the cam 36, freeing the bearing block 39. By employing the intermediate spring 38, variations of current strength in the magnet are not objectionably manifested in irregular bearing of the lever 3' against the cam, but such action is always positive irrespective of such variations as may occur in the circuit.

My invention is also readily applicable to the so called roller timer. In Figs. 6 to 10 inclusive is shown the usual roller timer in so far as concerns its general construction. The frame or casing 4' has the insulated contacts 16' symmetrically arranged concentrically about the timer shaft 12 on which is mounted a head portion 11' carrying the usual pivotal yieldable roller contact arm 41 adapted to successively engage contact segments 16'. In timers of this type as heretofore constructed, the roller arm 41 is held extended by a suitable spring,

for contact service as the head 11^a is revolved, and there is no provision for repressing the roller arm when the timer is not in ignition service. To accomplish such object I horizontally pivotally mount between posts 42 on the head piece 11^a a foot piece 43, the pivot 43^a of which, fixedly carried by the foot, extends beyond one of the pivotal posts or bearings 42 and is provided with a lever arm 44 depending at an angle to the plane of the foot 43. Connecting this arm 44 and the tail 45 of the roller arm is a spring 38^a, and also leading from the forward end of the roller arm to the head 11^a is a spring 40^a which normally holds the roller arm and contact roller 2^a in a retracted or non-contact position. Mounted preferably in the cover 46 of the timer is an electro magnet 23^a having a reciprocable plunger armature 22^a the lower reduced end of which depends into pivotal point engagement with the foot piece 43 (see Figs. 7 and 9).

The ignition circuit for the roller timer is shown in Fig. 10. The segmental contacts 16^a connect with individual trembler coils 27^a which in turn are connected in the primary or battery circuit 24^a. The roller contact arm 41 is preferably grounded, while the electro magnet, connected at 25 to the battery circuit, is also grounded at 26 (see Fig. 10^a). Closing of the switch 31 connects the battery 24 in ignition circuit commensurately completed and broken by travel of the roller contact 2^a over segments 16^a. Placing the battery in circuit energizes the magnet 23^a so that the plunger armature is impelled downwardly, as shown in Fig. 9, in such manner as to depress the foot piece 43 and swing the arm 44 away from the tail of the roller arm, thereby placing the spring 38^a under tension and moving the roller arm into extended or operative position for contact service, as shown in Fig. 8. Immediately upon breaking of the circuit 24^a or opening of the switch 31 and resultant deenergizing of the magnet 23^a the spring 40^a will swing the roller arm inwardly to an inoperative or non-contact position, causing the tail piece 45 to swing outwardly and return the foot piece 43 and armature 22^a to the normal position shown in Fig. 7. It thus will be noticed that the head 11^a is free to revolvably travel without liability of contractual engagement of the roller contact 2^a and contacts 16^a after the timer has been brought out of ignition service, thus obviating wear of roller and segments, incident to unnecessary extended travel of the timer in operative contact condition. By mounting the magnet in the cover or casing of the timer and bringing its armature into engagement with the foot 43, and pivotally on a line coincident with the axis of the timer shaft, said magnet remains stationary

with respect to the travel of the head 11^a, thus affording simple or fixed electrical connections of the magnet with its circuit.

A further modification of my invention is shown in Fig. 11. This timer or controller is of the well known spring arm class in which contact is made through a revolving cam 10^a. The cam has the usual uniformly arranged projections 13^a which wipe over a projecting portion or contact point 2^a of a yieldable arm 3^a. A primary circuit 24^a including vibrator coil 27^a connects the arm 3^a with the battery 24 through switch 31, while the cam 10^a is grounded. A further or shunt connection 47 connecting with the primary circuit or battery circuit at 25^a leads to the magnet 23, the core of which lies in juxtaposition to the extended terminal portion 3^b of the contact arm 3^a; the magnet being grounded at 26 as described above. It will be seen that with the battery connected in circuit, the magnet 23 will attract and hold the spring arm 3^a in a position permissive of the projections 13^a of the cam acting on the projection 2^a of the arm for periodical completion of the ignition circuit. With non-activity of the magnet, it will be apparent that the spring arm will, by its own resiliency, move away from and out of contractual relationship with the cam, thus permitting the cam to rotate without continual vibration and resultant wear and tear of the arm, when use of the timer is discontinued. In this partly diagrammatic view is also shown a distributor 29 connected to the secondary winding of the vibrator coil 27^a.

The regular multi-arm controller also presents a construction in which my invention may be advantageously embodied. Figs. 12 to 16 show a multiple-arm timer or controller in which provision is made, by my invention, for uniformly bringing the contact arms out of the path of the revoluble contact cam. The usual timer shaft 12 carries a single projection cam 48 which rotates for successive contact with projections or contact points 2^b of spring contact arms 49 equidistantly disposed about the cam 48. Each of the arms 49 connects with vibrator coils 27^a as in the case of the timer shown in Fig. 10. However, for convenience of illustration, in Fig. 12 I have shown the device as having only two of the arms connected to coils, it being understood that all contact arms may be likewise connected. The projecting contact points 2^b are preferably formed at the base of the blades or contact arms 49 as shown in Figs. 15 and 16, the blade extending above such point sufficiently to provide a bearing surface 50 adapted to coöperate with which, for distension of the contact arms, is an angular cam member 51. This cam member 51 is preferably pivoted to a bracket 52 leading

from the base of the timer frame or casing 53 instead of being pivoted to the timer shaft, for the purpose to be hereinafter described, and is disposed concentrically with 5 the timer shaft. Fixedly carried by the cam 51 is a lever arm 54 having an armature 55 for association with the electro magnet 23. A spring 56 is connected to the lever 54 and tends to hold the armature 55 10 away from the magnet. The magnet 23 is connected at 25 and grounded in the battery circuit, as above described, and upon energizing of the same the armature 55 will be drawn toward the magnet 23 so as to shift 15 the arm 54 and the cam 51 to a position non-impedimental of the resilient contactual function of the spring arms 49 under the action of the traveling cam 48. Disconnection of the battery 24 and deenergizing of 20 the magnet allows the spring 56 to shift the arm 54 and rotatively shift the cam 51 to such angular position as will cause the portions 57 to bear against and distend the contact arms 49 to such a position as will free 25 the projections 2^b from contactual engagement with the cam 48. The shifting cam 51 is preferably made of insulating material, so as to prevent short circuiting from the contact arms and to obviate the necessity of 30 otherwise insulating the parts associated with said shifting cam. And by mounting said cam 51 on a pivot separate from the timer shaft, liability to accidental shifting of the cam by the shaft is avoided.

35 It will be apparent from the foregoing description that my invention is capable of being greatly varied by those skilled in the art without departing therefrom. The arrangements of the controlling magnet and 40 circuits, and the construction and relative positions of the parts as shown and described, are merely used as typical embodiments of the broad principle of my invention of overcoming continued mechanical 45 working of the controller or timer after it has been taken out of ignition service.

Having thus described my invention what I claim and desire to secure by Letters Patent is:

50 1. In ignition controllers for explosive engines, a plurality of electric contacts, mechanism for actuating the contacts to effect opening and closing of the ignition circuit and means for rendering said actuating mechanism ineffective during operation of the engine and non-use of controller.

2. In ignition controllers for explosive engines, a lever, an electric contact associated therewith, a second electric contact, 60 means for shifting the lever for engagement of one contact with another, and mechanism for rendering the lever inoperative during operation of the engine and non-use of the controller.

65 3. In ignition controllers for explosive

engines, a lever, an electric contact associated therewith, a second electric contact, means adapted to engage and shift the lever for engagement of one contact with another, and mechanism for shifting the lever to an 70 inoperative position during operation of engine and non-use of controller.

4. In ignition controllers for explosive engines, a movable electric contact, a relatively fixed contact, means for bringing the movable contact into engagement with the fixed contact, and mechanism for maintaining operative association of the said means and movable contact, and adapted, when the controller has been brought out of service, to 80 terminate such operative association.

5. In ignition controllers for explosive engines, a plurality of contacts, a magnet adapted to maintain association of the contacts, permissive of contactual engagement, 85 and means for bringing the contacts out of such operative relationship, dependent for operation upon non-use of the controller.

6. In ignition controllers for explosive engines, a shiftable lever, an electric contact carried thereby, a relatively fixed contact, a second lever adapted to operatively shift the first lever for contactual engagement, and means for discontinuing the operative association of the levers upon withdrawal of 95 the controller from service.

7. In ignition controllers for explosive engines, a shiftable lever, an electric contact carried thereby, a relatively fixed electric contact, a revoluble member for actuating the lever to effect engagement of a contact with another, and means for bringing the lever out of operative association with the revoluble member.

8. In ignition controllers for explosive engines, a shiftable lever, an electric contact carried thereby, a relatively fixed electric contact, a second lever associated with the first lever for operative shifting of the first lever to effect engagement of a contact with another, means for actuating the second lever, and mechanism for bringing the second lever out of operative association with the actuating means.

9. In ignition systems for explosive engines, an ignition circuit, a controller, and means for rendering the controller non-operative during operation of the engine.

10. In ignition systems for explosive engines, an ignition circuit, a controller, and 120 electrically controlled means for rendering the controller non-operative during operation of the engine.

11. In ignition systems for explosive engines, an ignition circuit, a controller, means 125 for rendering the controller non-operative during operation of the engine, and electrical mechanism for controlling the said means.

12. In ignition systems for explosive engines, an ignition circuit, a controller, and 130

magnetically controlled means for rendering the controller operative and non-operative during operation of the engine.

13. In ignition systems for explosive engines, an ignition circuit, a controller, means for rendering the controller non-operative during operation of the engine, and an electro-magnet for controlling said means.

14. In ignition systems for explosive engines, an ignition circuit, a controller, means for rendering the controller non-operative during operation of the engine, and an electric magnet connected in the ignition circuit and adapted to control the said means.

15. In ignition systems for explosive engines, an ignition circuit, a controller, means for rendering the controller non-operative during operation of the engine, and an electro magnet having a winding in shunt with the ignition circuit and adapted to control the said means.

16. In ignition systems for explosive engines, an electric circuit, a source of energy therefor, a controller, means for rendering the controller operative and non-operative, and electrical mechanism for controlling the said means, dependent for operation upon connection of the circuit with the source of current energy.

30 17. In ignition systems for explosive en-

gines, an electric circuit, a controller comprising essentially a plurality of contacts and means for mechanically actuating the contacts, and electrically controlled mechanism for controlling the mechanical operation of the contacts.

18. In ignition systems for explosive engines, an electric circuit, a controller comprising essentially a plurality of contacts and means for mechanically actuating the contacts, and electrically controlled mechanism for rendering the contact actuating means non-operative during operation of the engine.

19. In ignition systems for explosive engines, a circuit, a source of energy therefor, a controller comprising essentially a plurality of electric contacts and means for mechanically actuating the contacts, and electrically controlled mechanism for rendering the controller operative and non-operative, dependent respectively upon connection and disconnection of the circuit with the current source.

In testimony whereof I have hereunto set my hand.

RICHARD VARLEY.
